AMOS MORLEY, OF ADDISON, MICHIGAN.

Letters Patent No. 95,254, dated September 28, 1869.

IMPROVEMENT IN HORSESHOE-NAIL CLINCHER

The Schedule referred to in these Letters Patent and making part of the same.

To whom it may concern:

Be it known that I, AMOS MORLEY, of Addison, in the county of Lenawee, and State of Michigan, have invented a new and useful Improvement in Horseshoers' Nail-Clinchers; and I do declare that the following is a true and accurate description thereof, reference being had to the accompanying drawings, and to the letters of reference marked thereon, and being a part of this specification.

The nature of this invention relates to an improved device for clinching or upsetting the ends of the nails driven through a horse's hoof for securing the shoe to the same.

It consists in the arrangement, on a proper handle or stock, of a compound lever, operating a serrated cam, for turning down and clinching the nail to its position; also, in the general arrangement of its parts, as hereinafter more fully shown and set forth.

In the drawings—

A A' represent the stock or handle of my device, provided, at its lower end, with serrations a.

Over the lower end is slipped a clamp, B, provided with internal notches or serrations b, to engage with those on the stock, so that it may be adjustable thereon.

The clamp is furnished, on the side of its slot opposite its serrations b, (which are shown in outline,) with a spring, b', to compel its engagement with the serrations a, and thus retain it in position.

The clamp is also serrated on its upper edge, so that

the head of the nail being operated upon will enter the serrations and prevent its slipping.

Pivoted in a longitudinal slot in the body of the tool, at c, is a lever, C, whose shorter arm is a geared segment, c'.

Pivoted at d, in the same slot, is a lever, D, whose shorter arm is a serrated cam, D', and whose longer arm is provided with gear-teeth d', on its end, to engage with the teeth c' of the lever C.

By bringing the lever C toward the lever A', the cam D' will be caused to move downward and inward.

To operate the device, the horse being shod, and the nails ready for clinching, the shoer takes his hoof on his knee. Taking the levers A' and C in one hand, with the other he adjusts the clamp B on the stock, bringing the serrations in its upper edge against the head of the nail, and the cam D' with its base on the end of the nail. He then draws the lever C toward the lever A', when the cam will turn down and clinch the nail-end to the proper position.

A spring, E, may be placed between the levers, to throw them apart, if desired.

What I claim as my invention, and desire to secure by Letters Patent, is—

As a new article of manufacture, the horseshoe-nail clincher above described, constructed, arranged, and operating as set forth.
